UNITED STATES PATENT OFFICE.

JOHN S. GILLIES, OF MANILA, PHILIPPINE ISLANDS, ASSIGNOR OF ONE-HALF TO METCALF A. CLARKE, OF MANILA, PHILIPPINE ISLANDS.

DEFIBRATING-MACHINE.

No. 832,476.

Specification of Letters Patent.

Patented Oct. 2, 1906.

Application filed September 27, 1905. Serial No. 280,362.

To all whom it may concern:

Be it known that I, JOHN S. GILLIES, a citizen of the United States, residing at Manila, in the Philippine Islands, have invented certain new and useful Improvements in Defibrating-Machines; and I do hereby declare the following to be a full, clear, and exact description of the invention, such as will enable others skilled in the art to which it appertains to make and use the same.

This invention relates to improvements in machines for the treatment of fibrous plants, and is especially adapted for use in defibrating or separating the refuse matter from the fibers contained in the stalks of the abaca and similar fiber-bearing plants.

The principal object of the invention is to provide means for giving a rotary motion to the clean portion of the fibrous material, whereby the individual fibers of the cleaned portion are slightly twisted together in a loose strand during the process of decortication, thereby practically eliminating breakage of the fibers by the increased strain thereon, owing to the separation of the integument and viscous refuse matter therefrom.

Another object of the invention is to so mount the knives or scrapers with relation to each other that during the passage of the abaca therebeneath one of the knives or scrapers will act on one face of the stalk and the next knife will engage the opposite face thereof, whereby the greater quantity of the integument and viscous matter is initially gouged out of the stalk, a more complete separation being attained during the passage beneath the second knife or scraper.

Other objects and advantages will appear from the following specification, and to more fully understand the invention reference is had to the accompanying drawings, illustrating an application of the same, in which like figures designate the same parts in the several views, and in which—

Figure 1 is a plan view of my improved apparatus. Fig. 2 is a side elevation of same. Fig. 3 is a plan view of the operating-frame carrying the twister-head. Fig. 4 is a section along the line 4-4 of Fig. 1. Fig. 5 is an end elevation of the clamp or twister-head. Fig. 6 is an end elevation of one of the scrapers or knives, showing means for elevating and locking same; and Fig. 7 is a fragmentary

perspective view of a leaf or stalk of the abaca-plant.

55

1 is a suitable frame, preferably of angle-iron construction.

2 and 3 are forward and rear shafts, respectively, journaled in the frame and provided with sprocket-wheels at each side of 60 the frame, around which reeve the sprocket-chains 4.

5 is a gear-wheel on the end of the sprocket-shaft 2, driven by the intermeshing pinion 6, mounted on the shaft 7, provided with the 65 operating cranks or handles 8.

9 is a depending hanger or plate carried by the frame, in which one end of the shaft 7 may be journaled.

The shaft 3, carrying the sprockets at the 70 rear end of the machine, may also be suitably journaled in the depending hangers or plates 10, which plates in the present instance are slotted, as at 10^a, to receive the journal-boxes of the shaft, which journal-boxes have 75 connected thereto adjusting means, comprising in the illustration the bolt 11 and nut 12, associated with the frame of the machine to take up and adjust the slack of the 80 sprocket-chains, if desirable.

13 is a shelf or table at the forward end of the machine and disposed substantially in the same plane as the lower path of travel of the sprocket-chains, and 14 is a knife or scraper located in the inclining guideways 85 15, extending from the outer end of the shelf or table 13 upwardly and rearwardly toward the top of the frame.

16 is a second knife or scraper mounted at the rear end of the machine and suitably supported by standards or uprights forming a 90 part of the frame 1.

In Fig. 6, 1^a designates the uprights or continuations of the frame 1, preferably of angle-iron, to which is adjustably secured the 95 cross-piece or angle-plate 1^b by means of the bolt members 17, secured to the uprights 1^a and screw-threaded, as at 17^a, to receive locking-nuts engaging the lateral web of the cross member 1^b. As the knife is hung from this cross member 1^b, it will be seen that these bolt members 17 afford a means for regulating the pressure of the knife or scraper against the material being treated.

16^a represents vertical guide-plates carried 105 by the frame 1^a adjacent slots cut in the web

and forming guideways through which the ends of the knife 16 reciprocate during the upward swing of the knife, the downward movement of the knife being adjustably controlled by the set or abutment screws 18, passing through a table or shelf 19, immediately below the knife 16, said table or shelf being supported on the main frame by suitable brackets or angle-plates and preferably 5 composed of suitable wood, such as lignum-vitæ. The knife is suspended by the hanger bars or arms 20, pivotally secured at one end to the cross member 1^b and at their other ends to the knife or scraper 16. These 10 hanger bars or arms 20 are also pivotally connected to each other by means of the bar 21, provided at one end with an operating-lever 22, pivotally secured in a bracket 23, a portion of the bar 21 being notched, as at 24, to 15 engage a pin 25, carried by the frame when the knife is set in its working position.

26 is a rack extending longitudinally along the top of one side of the frame, and 27 is a rail extending longitudinally along the other 20 side of the frame, the purpose of which will hereinafter appear.

28 is a twister-head frame in the form of a channel-iron having its lateral web cut away to receive certain operating parts. On one 30 end of this twister-head frame is located a grooved guide-wheel 29, adapted to ride along the rail 27. At the other end of the twister-frame is provided the rotary stud-shaft 29^a, carrying at one end the pinion 30 and at the other end the beveled gear-wheel 31.

The vertical longitudinal webs 28^a of the twister-head frame are apertured, as at 32, (see Fig. 4,) to receive the spindles 33, carrying the gear-wheels 34, and projecting on one side laterally beyond the twister-head frame and carrying at this projecting end a clamp 35, comprising the apertured main member, in which is adjustably mounted the clamping-block 36, carried on the end of the adjustment-screw 37, which adjustment-screw has a reduced end annularly grooved, as at 37^a, forming a shoulder 37^b, whereby the clamping-block 36 may be securely held with reference to the adjustment-screw 37 by means of the set-screw 38, carried by the clamping-block 36 and adapted to seat in the annular groove 37^a of the adjustment-screw.

To prevent the possible slipping of the 55 abaca-stalk between the jaws of the clamp, irrespective of what specific form of clamp is used, I find it desirable to interpose, as at 35^a 36^a, Fig. 4, a lining of gunny-sacking or other textile material, forming non-slipping 60 contacting surfaces, and while other textile materials or rubber may be employed I find from experience that gunny-sacking best subserves the end. This lining may be secured to the faces of the clamping-jaws in any suitable way—for instance, by a cement.

As clearly shown in Figs. 1 and 3, the gear-wheels 34, carried by the spindles 33, intermesh, and the end one of these gear-wheels, which for identification is designated 34^a, surrounds the studded end 39 of the beveled gear-wheel 40, the gear-wheel 34^a and the beveled gear-wheel 40 being interlocked, as by the splining-screw 41.

42 is one of a plurality of bars extending transversely of and connected with the 75 sprocket-chains, and 43 represents connecting-rods yieldingly secured to the web 28 of the twister-head frame, as by means of the coil-springs 44, the other end of the rods being provided with suitable securing means—such as a 80 hook 43^a and a set-screw 43^b, if desired. To prevent the rear end of the twister-head frame from sagging when passing along the lower side of the sprocket-chain, I provide any suitable means, illustrated in Fig. 1 by a hook-and-eye or link connection 42^a between the sprocket-chain and twister-head frame, constructed to allow horizontal play for the twister-head frame, but to prevent vertical play thereof, or the rear end of the twister-frame may be yieldingly connected with a 85 cross-bar similar to 42 to accomplish the same end.

In Fig. 7, for the purpose of illustration, 45 designates the integument of an abaca-stalk, 95 45^a the glutinous portion forming the body of the stalk, and 45^b the fibrous strands.

In each clamp member of the twister-head frame a strip of the abaca-stalk is firmly secured between the clamping-block 36 and the bottom of the frame 35, with the surface 45 preferably lying alongside the face of the clamping-block 36. In this position the knife 14 is raised in its guideways and the clamping-frame secured, by means of the connecting-bars 43, to one of the cross-bars 42 on the underneath side of the sprocket-chain, the parts being in the position shown in dotted lines in Fig. 2. The knife or scraper 14 is then lowered, and the pressure of this knife might be regulated in any way—for instance, by its own weight or by operating mechanism similar to that described with reference to the knife 16. It will be obvious now that upon the operation of the cranks in the direction indicated by the arrows the strips of abaca will be dragged along in the path of travel of the lower portion of the sprocket-chains, while the knife or scraper 14 is gouging out the glutinous pulpy matter 45^a, fairly 110 cleaning the fiber of the greater part of the refuse matter.

When the twister-head frame passes around the sprocket-wheels at the rear end of the frame, the knife 16 is elevated sufficiently 115 to allow the same to pass thereunder, when it is again pressed down into position on the strips of abaca resting on the surface of the leaves opposite to that on which the knife 14 rested, the downward movement of the knife 130

being limited by the adjustment-screws 18 to prevent abrasion of the fibrous material and the degree of pressure of the knife on the abaca being regulated, as before described, 5 by the adjustment-bolt members 17. When in this position, the abaca is lead beneath the second knife 16 in the comparative form of a flat ribbon, the greater portion of the viscous and pulpy matter having been extracted, 10 and upon the continued rotation of the cranks in the same direction the twister-head frame will move forwardly along the machine, and the pinion 30, engaging the rack 26, will, through the intermediate gears 40, 34^a, and 15 34, cause the respective spindles 33 to slowly rotate during the forward movement of the twister-head frame, thereby conjointly imparting a slow rotary motion to the cleaned fibrous strands during the final process of denudation, twisting them together in a loose 20 strand and relieving the individual strands of fiber from strains independent of the joint strand.

While the foregoing illustrates an operative application of the invention, it will be understood that I do not wish to restrict myself to the exact details illustrated and described, as it is obvious that various modifications might be made without departing 25 from the spirit of the invention—for instance, any suitable driving power might be employed other than the cranks, as shown.

What I claim is—

1. The combination in a machine for defibrating fibrous plants, of means for separating the waste vegetable matter from the fibers of the plant, and means for twisting said cleaned fibers in a strand while the remainder of the plant is being denuded of waste matter. 35 2. The combination in a machine for defibrating fibrous plants, of means for denuding the fibers of waste matter, a support rotatably mounted transversely of the path of travel of the plant being cleaned and co-operating therewith to impart a twisting motion to the cleaned fibers during the operation of denuding, and means for rotating said support. 40 45

3. The combination in a machine for defibrating fibrous plants, of means for denuding the fibers of waste matter, a movable support and means for operating same, a rotatably-mounted twister-head carried by said support and adapted to engage the fibrous plant, and means for rotating said twister-head during the travel of said movable support. 50 55

4. The combination in a machine for defibrating fibrous plants, of means for denuding the fibers of waste material, a rack carried by 60 the frame of said machine, a movable support operative adjacent said rack and means for operating same, a pinion carried by said support and engaging said rack, a rotatably-mounted twister-head carried by said support and adapted to engage the plant being 65

treated, and gearing between said twister-head and pinion.

5. The combination in a machine for defibrating fibrous plants, of means for denuding the fibers of waste matter, rotatably-mounted 70 twister-heads adapted to engage the plants being treated, and means for rotating said twister-heads during the operation of denuding.

6. The combination in a machine for defibrating fibrous plants, of a suitable framework and an endless traveler carried thereby, means for denuding the fibrous plant of its vegetable matter, a twister-head frame resiliently connected with said traveler, a 80 twister-head mounted in said twister-head frame and adapted to engage the plant being treated, means for operating said endless traveler, and means for rotating said twister-head. 85

7. The combination in a machine for defibrating fibrous plants, of a suitable framework, sprocket-wheels journaled at opposite ends thereof, endless traveler-chains carried by said sprocket-wheels, means for denuding 90 the plant of waste vegetable matter, a cross-bar connecting said traveler-chains, a twister-head frame, spring connections between said twister-head frame and said cross-bar, a plurality of rotatable twister-heads mounted in 95 said twister-head frame and adapted to engage the ends of the plants being treated, a rack, a pinion carried by said twister-head frame and engaging said rack, gearing between said twister-heads, and gearing 100 between one of said twister-heads and said pinion.

8. A machine for defibrating fibrous plants, provided with a twister-head substantially as described, said twister-head 105 comprising a clamping member provided on its contacting faces with a lining of non-slipping material.

9. A machine for defibrating fibrous plants, provided with a twister-head substantially as described, said twister-head comprising a clamping member provided on its contacting faces with a lining of gunny-sacking. 110

10. The combination in a machine for defibrating fibrous plants, of knives or scrapers disposed out of vertical alinement on opposite sides of the path of travel of the plant being treated, means for drawing said plant along said knives, and means for twisting the 115 cleaned fibers while the remainder of the plant is being operated upon by said knives or scrapers, substantially as described. 120

11. The combination in a machine for defibrating fibrous plants, of a suitable frame 125 and endless conveying means extending longitudinally of said frame, a knife or scraper arranged at one end of said frame, substantially in the lower plane of travel of said conveyor, a second knife or scraper at the oppo- 130

site end of the machine arranged in the upper path of travel of said conveyer and adapted to engage the plant on the opposite face from said first knife, and means carried by said 5 conveyer to engage the plant being treated and operate the latter in contactual relation with said knives.

In testimony whereof I affix my signature in presence of two witnesses.

JOHN S. GILLIES.
